ARM CHAIR

Lester S. Pearl, 401 Beauwood Court, Olivette, Mo.

Filed July 22, 1963, Ser. No. 75,921

Term of patent 7 years

(Cl. D15—1)

The back of the chair is plain and unornamented.

I claim:

The ornamental design for an arm chair, substantially as shown and described.
